UNITED STATES PATENT OFFICE

HUGH D. FITZPATRICK, OF GLASGOW, SCOTLAND, ASSIGNOR TO U. S. SLICING MACHINE COMPANY, OF LA PORTE, INDIANA, A CORPORATION OF INDIANA

SLICING MACHINE GUIDE

Application filed February 7, 1929, Serial No. 338,168, and in Great Britain February 9, 1928.

The present invention relates to slicing machines of the type in which the substance to be sliced is moved past a slicing knife whereby slices are cut in succession from the substance, the carriage being provided with bearings mounted on one or more guides fixed to the base of the machine.

One object of this invention is to provide a lubricating means so that the bearing surfaces of the guides may be efficiently lubricated.

Another object of this invention is to provide a reservoir for the lubricant in close proximity of the guide so that the lubricating device may scoop oil therefrom and supply it to the bearings on the guides.

Another object of this invention is to provide a means whereby a lubricant is automatically supplied to the bearing surfaces as the carriage reciprocates, a very simple and effective means being provided for this purpose.

Another object of this invention is to provide a tubular member or members on the bearings for supplying lubricant to the bearing surfaces.

Other objects of the invention will appear hereinafter, the novel features and combinations being set forth in the appended claims.

In the drawing—

Fig. 1 is a side elevation of a portion of a slicing machine embodying my invention, with parts thereof in section;

Fig. 2 is a longitudinal cross-section through the bearing, guide, and lubricant holding trough;

Fig. 3 is a fragmentary end view of one of the bearing members, with the lubricant trough therefor shown in section;

Fig. 4 is an end view similar to Fig. 3 showing a modification of the invention; and

Fig. 5 is a fragmentary longitudinal section of the device shown in Fig. 4.

Referring to Figs. 1 to 3, inclusive, the device as illustrated comprises a base 1, a carriage 2, having bearings 3 slidable on the guides 4 mounted at their ends in brackets 5 carried by the base 1. The carriage 2 has the usual cross-slide 6 for feeding the material

10 to be sliced toward the slicing knife, not shown. The supports 7 on the cross-slide 6 carry the clamp 8 which is manipulated by the handle 9 to clamp the material to the cross-slide. Beneath each of the guide rods 4 55 is located a trough or receptacle 11 for a lubricant 17 and this trough is bolted to the base 1 as at 12 and has a cover 13 with a longitudinal slot therein fastened to the receptacle 11 by means of screws, or the like. 60

Each of the bearings 3 has a spiral groove 14 located on its inner surface adjacent the guide rod. Tubular members 15 are screw-threaded in bosses as at 16 on the bearing 3 at opposite ends thereof and each is adapted 65 to communicate with one end of the groove 14 to form a continuous passage from the open end of one tubular member through the bearing to the open end of the other tubular member. The tubular members 15 extend below 70 the surface of the lubricant 17 in the trough 11 and as the carriage reciprocates on the guide rods 4 the lubricant is forced through the passage formed by the tubular members 15 and the groove 14, first in one direction 75 and then in the opposite direction. This distributes the lubricant along the rod and furnishes a very efficient and durable construction for keeping the bearing surfaces well lubricated at all times without the necessity 80 of using a great number of parts or special lubricating devices which require constant attention. All that is necessary in devices of this kind is to fill the troughs 11 with a lubricant, as needed. 85

It will be noted that as the carriage 2 reciprocates a suction is created in one of the tubular members 15 and that a pressure is built up in the other tubular member. Both of these forces therefore assist each other 90 in carrying the lubricant through the groove 14.

It will be understood that there is a trough under each of the guide rods and that any suitable mechanism may be used to reciprocate the carriage. A very common means for doing this being a crank and pitman connection to the table which is operated by a rotating shaft. 95

In Fig. 4, is shown a modification in which 100

the tubular extensions from the groove are made integral with the bearing member, the device as illustrated here showing the base 1 and the guide 4 supported by the bracket 5, the same as in the embodiment shown in Figs. 1 to 3, inclusive, but in this instance the carriage 2' has a bracket 19 carrying a bearing 20 fastened thereto which slides on the guide 4. The bracket 19 also has pivotally connected thereto a pitman 18 used to reciprocate the carriage in a well-known manner. The trough for the oil in this instance comprises a tubular member 21 surrounding the guide rod 4 and carried by brackets 22 mounted on the rods 4 and has a slot 23 through which a portion of the bracket 19 is adapted to extend so as to provide a connection to the bearing 20.

The oil groove 24 on the inner surface of the bearing 20 is similar to the groove 14 shown in Figs. 1 to 3, inclusive. Cast integral with the bearings 20 are the tubular members 25, the openings of which are in communication with the groove 24 so that as the carriage is reciprocated the oil or other lubricant is forced through the groove in the same manner as in Figs. 1 to 3, inclusive.

This modification also has the advantage of having a covering means for the guide rods throughout substantially its entire length, this covering consisting of the upper portion of the tubular member. It is very important that dust, dirt and other foreign matter be kept from falling upon the guide rods so as not to contaminate the surface of the rod and injure the bearing surfaces of the rod and the bearing on the carriage, and the covering means just described is very efficient for that purpose. It is understood, however, that the slot 23 may be in other positions around the periphery of the tubular member 21 and still be within the spirit of the present invention.

Obviously those skilled in the art may make various changes in the details and arrangement of parts without departing from the spirit and scope of the invention as defined by the claims hereto appended and I wish therefore not to be restricted to the precise construction herein disclosed.

Having thus fully disclosed an embodiment of my invention, what I desire to secure by Letters Patent of the United States is:

1. A slicing machine comprising a base, a guide on said base, a table adapted to reciprocate above said base having a bearing co-operating with said guide, a groove in said bearing, a lubricant trough, and extensions on said bearing having openings communicating with said groove, said extensions adapted to extend into the lubricant carried by the trough to convey the lubricant to the groove as the table reciprocates.

2. A slicing machine comprising a fixed guide, a bearing on said guide supporting

a table, means for moving said table, a groove in said bearing, a lubricant trough on said guide, and an extension on said bearing having an opening adapted to receive and convey lubricant from said trough to said groove as said table reciprocates. 70

3. A slicing machine comprising a support, guides on said support, a table, slide members on said table co-operating with said guides, a groove in each of said slide members, and a tubular member on each of said slide members having an opening therein communicating with said groove, and a trough for holding a lubricant, said tubular members being adapted to scoop the lubricant from said trough as the table reciprocates. 75 80

4. A slicing machine comprising a support, guides on said support, a table, slide members on said table co-operating with said guides, a groove in each of said slide members, a tubular member at each end of each of said grooves having openings communicating therewith, and a trough on said guides for holding a lubricant, said tubular members being adapted to scoop the lubricant from said trough as the table reciprocates. 85 90

5. A slicing machine comprising a substance support, a guide, a slide member on said substance support and engaging said guide, a lubricating trough, and a lubricating groove in said slide member communicating with said guide and said trough, said groove extending into said trough so that when lubricant is in said trough the lubricant will be in communication with the ends of said groove, said groove being so arranged as to cause the lubricant to be forced therethrough when said substance support is moved along said guide as long as the ends of said grooves are in communication with the lubricant, the lubricant being carried through said groove partly by suction created at one end of said groove and partly by pressure exerted at the other end of said groove, said suction and pressure tending to move said lubricant in the same direction. 100 105 110

6. A slicing machine comprising a reciprocating table, a bearing member on said table, a guide for guiding said bearing, said bearing having a lubricating conduit formed in said bearing and having a portion thereof in communication with said guide, hollow extensions on said bearing having the hollow portions thereof communicating with said conduit at opposite ends thereof, and a lubricating trough arranged adjacent said guide, said hollow extensions extending into said trough a sufficient distance so that when lubricant is in said trough the openings in said hollow extensions will receive lubricant as the carriage reciprocates, the reciprocation of said carriage causing the lubricant to be forced through said conduit partially by pressure exerted on the lubricant in one of 115 120 125 130

said extensions and partially by suction created in the other of said extensions due to the reciprocation of said carriage.

7. A slicing machine comprising a guide rod, a slicing machine table having a tubular member surrounding said guide rod, a reservoir beneath said guide rod, a groove in said tubular member for conveying a lubricant to the bearing surface of said tubular member, and a conduit having an opening communicating with said groove extending in such a direction as to scoop a lubricant from said reservoir and convey it to said groove.

8. A slicing machine comprising a table, a guide, a tubular member surrounding said guide and having a bearing surface thereon, a groove in said tubular member for conveying liquid to the bearing surface of said tubular member, and a tube on said tubular member at each end of said groove adapted to scoop oil from an oil reservoir therebeneath and deliver it to said groove.

9. A bearing for slicing machine tables comprising a tubular member adapted to surround a guide rod and having a bearing surface thereon, a groove in said tubular member for conveying liquid to the bearing surface of said tubular member, and a tube at one end of said groove adapted to scoop oil from an oil reservoir therebeneath and deliver it to said groove.

10. A slicing machine comprising a support, guides on said support, tubular members surrounding said guides and extending substantially the entire length thereof, each having a longitudinal slot therein, a table, bearing members on said table having portions extending through said slots and engaging said guides, grooves in said bearing members adjacent said guides, and conduits having openings therein communicating with said grooves and extending in a direction to scoop up lubricant and convey the same to the bearing surfaces of said bearing members, said tubular members forming covers over said guides to protect said guides from foreign matter which might otherwise fall thereon and injure the bearing surface thereof.

11. A slicing machine as claimed in claim 8 in which said tubes on the said tubular member are located at opposite ends of said tubular member.

12. A slicing machine as claimed in claim 8 in which said tubes on the said tubular member are integral with said tubular member.

13. A slicing machine as claimed in claim 8 in which said tubes on said tubular member are separate from said tubular member and are secured thereto.

14. A slicing machine as claimed in claim 8 in which said tubes on said tubular member are at opposite ends of said tubular member and in which said groove is a spiral groove.

15. A slicing machine comprising a base,

guides on said base, a reciprocating carriage, slide members on said carriage in engagement with said guides, grooves in those faces of said slide members which are in engagement with the guides, a lubricant holding trough between each of said guides and said base, a slot in each of said lubricant troughs, and means extending from said slide members through said slots adapted to scoop lubricant from said trough and convey it to said groove as the table reciprocates.

16. A slicing machine comprising a substance support, a guide rod, a bearing member embracing said guide rod and carried by said support, a groove in said bearing member in the face thereof which engages said guide rod and extending around said guide rod with the opposite ends thereof protruding downwardly and outwardly in the direction of travel of said support on said guide rod, and a lubricant trough located beneath said guide rod and adapted to contain lubricant to such a level that lubricant will be supplied to said ends of said groove as the support reciprocates along said guide rod.

17. A slicing machine comprising a base member, a reciprocating member, a bearing on one of said members cooperating with a guide on the other of said members, a lubricant receiving member adjacent said guide, a groove in said bearing having the ends thereof extending in the general direction of reciprocation of said member and communicating normally with the lubricant below the normal level of said lubricant in said lubricant receiving member, and means automatically operable by reciprocation of said carriage for conveying the lubricant through said groove in said bearing as long as one end of said groove communicates with the lubricant.

In testimony whereof I have signed my name to this specification on this 18th day of January A. D. 1929.
